UNITED STATES PATENT OFFICE.

OTTO PROCHAZKA, OF DETROIT, MICHIGAN.

ILLUMINATED HOUSE-NUMBER.

1,379,780.

Specification of Letters Patent. Patented May 31, 1921.

Application filed July 3, 1919. Serial No. 308,597.

To all whom it may concern:

Be it known that I, OTTO PROCHAZKA, a citizen of the United States of America, residing at Detroit, in the county of Wayne 5 and State of Michigan, have invented certain new and useful Improvements in Illuminated House-Numbers, of which the following is a specification, reference being had therein to the accompanying drawings.

10 This invention relates to illuminated house numbers and its object is to provide a simple and inexpensive device for detachably mounting a house number upon a porch globe so that when the latter is lighted the 15 number will be illuminated.

It is a further object of the invention to provide a device that is readily convertible for use with globes of either the ceiling or wall type.

20 In the drawings:

Figure 1 is a view in front elevation of a porch globe of the ceiling type to which the invention is applied;

Fig. 2 is a side view showing the application of the invention to a globe of the wall type;

Fig. 3 is a perspective view of the attachment removed from the globe.

In these views the reference character A 30 designates a porch globe engaging a house mounting B. C is a wire ring of a diameter slightly less than the maximum diameter of said globe so that said ring may rest upon the globe in either of the positions 35 shown in Fig. 1 and Fig. 2. Said ring is engaged by an angular supporting bracket D formed of bendable material, preferably sheet metal, the lower end of said bracket being bent to embrace the ring as indicated 40 at D', and being soldered thereto. The upper portion of said bracket is apertured at D² for engagement by a screw or other suitable means for fastening the bracket to the ceiling or wall upon which the mounting 45 B is secured. Diametrically opposite the bracket D, the ring C is formed with a series of equally spaced offsets E, from each of which is supported a metallic digit F of a house number, the preferred supporting

means being lugs G formed integral with 50 the digits F at their upper ends and adapted to be bent to loosely embrace the offsets E. Thus the members F may be very quickly secured to the ring to form any desired house number and may be readily replaced 55 or changed if desired. When the attachment is to be applied to a wall globe such as is shown in Fig. 2 the bracket D is bent as shown in said figure so that it may be secured to the wall rather than to the ceiling. While the globe A would form a support for the ring C even if the bracket D were omitted, it is preferred to employ said bracket, as without such provision the ring would be readily disarranged and result in 60 an unsightly appearance. The provision of the offsets in the ring prevent any shifting of the members F to or from each other so that the digits of the number will be always 65 equally spaced.

What I claim as my invention is:

1. In a device of the character described, the combination with a porch globe, of a ring embracing the upper portion of said globe, a bendable bracket secured to said 75 ring and attachable to the surface supporting the globe, and a series of digits depending from the ring at the front of the globe and forming a house number.

2. In a device of the character described, 80 the combination with a porch globe, of a series of digits arranged at the front of said globe to form a house number, a member supporting said digits, and means for securing said supporting member to either 85 a horizontal or vertical surface.

3. In a device of the character described the combination with a porch globe of a ring embracing the upper portion of said globe formed with a series of equally spaced 90 offsets at the front of the globe, a series of digits, and means for pivotally attaching the upper extremities of said digits respectively to said offsets to form a house number.

In testimony whereof I affix my signature.

OTTO PROCHAZKA.
